F. S. Snyder, INVENTOR
BY Victor J. Evans

ATTORNEY

UNITED STATES PATENT OFFICE

FRANK S. SNYDER, OF COUNCIL BLUFFS, IOWA

GARMENT

Application filed July 19, 1930. Serial No. 469,157.

This invention relates to a garment for wear by railway employees, farmers, truck drivers and other workmen who are engaged in such occupations as to be subjected to 5 soiling of their clothing in the carrying out of their tasks and therefore the present invention has as its primary object to provide a pair of trousers which may be worn under over-alls instead of the workman wearing 10 more expensive trousers beneath over-alls.

Another object of the invention is to provide a garment of this type so constructed that the entry of dust, mud and other foreign matter into the legs of the garment, 15 about the wearer's ankles will be effectually prevented so that the underwear will not become soiled by such foreign matter.

Another object of the invention is to provide a garment of the type referred to which 20 will fit snugly about the waist of the wearer and not require suspenders for holding it in place upon the wearer and which will at the same time fit the wearer in such a manner as to constitute effectually an abdominal support, and brace, permitting 25 perfect movement of the body of the wearer in performing his labors, and at the same time retaining the garment against displacement.

Another object of the invention is to provide 30 a garment of the class referred to, which may be removed from the person, wearing the same, without the necessity of removing his shoes.

This invention also consists in certain other 35 features of construction and in the combination and arrangement of the several parts, to be hereinafter fully described, illustrated 40 in the accompanying drawings, and specifically pointed out in the appended claim, it being understood of course that minor changes may be made so long as they fall within the scope of the claim.

In describing my invention in detail, reference 45 will be had to the accompanying drawings, wherein like characters denote like or corresponding parts throughout the several views, and in which:

Figure 1 is a perspective view illustrating

a pair of trousers constructed in accordance with the present invention.

Figure 2 is a detail sectional view taken substantially on the line 2—2 of Figure 1, looking in the direction indicated by the 55 arrows.

The trousers, so far as their general construction is concerned, do not differ from ordinary trousers and include a waist portion which is indicated by the numeral 1 60 and legs 2. About the waist portion there is disposed a flexible, relatively broad belt 3 which is stitched at a point intermediate its length, as indicated by the numeral 4, to the waist portion 1 of the trousers at 65 the rear thereof, and the belt is brought about the waist portion and preferably through the usual belt loops 5 and tightened about the waist of the wearer of the garment by the use of the usual buckle 6. In 70 order that the waist portion of the trousers may snugly conform to the body of the wearer, so that the belt will not be required to be unduly tensioned or tightened in order to hold the trousers against displacement, means is provided which will now be described. The means referred to 75 comprises one or more relatively broad bands 7 of elastic which are secured at their ends by stitching, as indicated by the numeral 8 to the inner side of the waist portion 1 of the trousers at the rear of said portion, in attaching this band or bands to the trousers, the ends of the band will be connected by the lines of stitching 8 at 80 points spaced a greater distance apart than the length of the band so that the rear portion of the waist of the garment will be more or less puckered as shown in the drawings.

The legs 2 of the trousers are preferably of a width, at their lower end portions, sufficient to enable them to be fitted or slid over shoes or boots worn by the workman who is to wear the garment, and in order that the lower ends of the legs 2 of the garment may be closed about the ankles of the wearer, a strap 9 is secured intermediate its ends by stitching or otherwise, as at 10 to preferably the inner side 95 100

of each leg near the lower end thereof, and a buckle 11 is provided at one end of the strap and the strap is adapted to be carried about the end of the respective leg and secured by the buckle in a manner of adjustment, as shown at the right in Figure 1, so as to pucker the lower portion of the trousers leg and cause the same to fit snugly about the garment.

10 From the foregoing description of the invention it will be evident that the trousers embodying the same may be made of inexpensive cloth material, and therefore the one using the same will not be liable to 15 have his underwear soiled by dust, dirt, and mud, and can accomplish this without the use of more expensive trousers.

It will be understood of course that the garment embodying the invention may, if 20 desired, be lined with the material from which blankets or other warm washable clothes are formed, so that the garment may be conveniently worn in cold weather.

What I claim is:—

25 A garment comprising the usual component parts of a pair of trousers, an elastic band secured at its ends to the inner side of the waist band of the trousers and disposed transversely across the rear seam of 30 the trousers, the elastic band holding that portion of the waist band which lies between the ends of the elastic band in a gathered condition, and a belt extending around the outer side of the waist band and 35 secured thereto.

In testimony whereof I affix my signature.

FRANK S. SNYDER.
